UNITED STATES PATENT OFFICE.

HARRY E. LA BOUR, OF CHICAGO HEIGHTS, ILLINOIS.

CENTRIFUGAL PUMP.

1,355,982.

Specification of Letters Patent. Patented Oct. 19, 1920.

Application filed March 11, 1918, Serial No. 221,644. Renewed August 12, 1920. Serial No. 403,155.

To all whom it may concern:

Be it known that I, HARRY E. LA BOUR, a citizen of the United States, residing at Chicago Heights, in the county of Cook and

5 State of Illinois, have invented a certain new and useful Improvement in Centrifugal Pumps, of which the following is a full, clear, concise, and exact description reference being had to the accompanying drawings, forming a part of this specification.

10 My invention relates to pumps and more particularly to pumps of the centrifugal type wherein the liquid is delivered under a head to the impeller, the device being employed in systems for conveying acids or

15 other corrosive liquids or fluids. Due to the corrosive nature of such fluids, I contemplate a centrifugal pump constructed in whole or in part of non-corrodible material. Particularly the interior parts of the pump are made of material that will not be affected by the fluid conveyed.

20 One of the disadvantages and difficulties of the prior art devices has been due to the formation of eddy currents and gas pockets within the pump, invariably causing the pump to become air or gas bound. A further difficulty heretofore encountered in 25 pumps of the class to which my invention relates has been that of properly balancing the impeller shaft to take up or control the end thrust away from the inlet that is created in pumps of this type, particularly 30 those wherein an admission opening is employed on only one side, due to the impact of the liquid against the impeller at the inlet.

35 It is an object of my invention to provide an improved pump of simple and durable construction, wherein all tendency to become air or gas bound due to the formation of eddy currents or suction pockets will be absolutely eliminated, consequently providing a pump of greatly increased efficiency.

40 A further object of my invention is the provision of means for controlling the direction and amount of end thrust created in the pump, the controlling means being provided according to the quantity of fluid to 45 be pumped and the speed of rotation of the impeller.

45 I accomplish the control of end thrust preferably by forming a central recess in the impeller blades at the point where the liquid enters. The edges of the impeller

defining the sides of the recess are preferably parallel to the axis of rotation of the impeller, and by making the recess of suitable depth I am enabled to control or eliminate end thrust. 60

A further object of my invention is the provision of a pump wherein the fluid will enter the impeller chamber with a minimum velocity of whirl which is so essential in 65 pumps of the centrifugal type.

70 In the preferred form of my invention I form all the interior parts of the pump of relatively non-corrodible material, such as lead when conveying sulfuric acid. I provide the pump with a removable head member thereby allowing easy access to the impeller chamber for clearing out dirt, for 75 repairs and for interchanging impellers according to the speed of rotation and the quantity of fluid to be pumped.

By the term "low head pump" used in the description and claims I refer to a pump of that class which depends for its action on the maintenance of the continuity of the 80 liquid column, and not on the switches.

I find this construction to be highly advantageous as it is simple, reliable and durable. I do not intend to be limited to the precise construction which I disclose herein, as it is apparent that the embodiment of 85 the invention may be widely varied.

In the accompanying drawings forming a part of this specification—

Figure 1 is a side elevation of the preferred form of my invention showing the pump connected directly to the shaft of a 90 motor;

Fig. 2 is a vertical sectional view taken on the plane of line 2—2 of Fig. 3;

Fig. 3 is a horizontal sectional view taken on the plane of the line 3—3 of Fig. 1;

Fig. 4 is a front elevation with the head member removed; and

Figs. 5 and 6 are diagrammatic views 100 illustrating the method of controlling the end thrust.

Referring to the drawings, the pump of my invention comprises a casing 1 and a head member 2, provided about their peripheries with flanges 3 and 4 respectively. The casing 1 and head member 2 are adapted to be clamped together by means of the bolts 5, with a suitable gasket gripped therebetween to insure a tight joint. A bed plate 105 or base member 6 is provided preferably integral with the casing 1, the casing being

provided with a suitable bore substantially in the center thereof for the reception of an impeller shaft 7.

The casing 1 is provided with a boss 8 preferably formed integral therewith and projecting therefrom, which is recessed or counterbored to form a stuffing box in which is lodged the packing 9 for forming a tight joint about the impeller shaft 7. The packing 9 about the impeller shaft 7 is placed inside the boss 8, a coöperating gland 10 serving to hold the packing firmly in place about the shaft 7.

The casing 1 is provided with a pair of lugs or wings 11 and 12 preferably formed integrally therewith and projecting therefrom on either side of the boss 8. The lugs or wings 11 and 12 serve to carry the gland adjusting eye bolts 13 and 14, the eye portions of which are adapted to be secured between the lugs 11 and 12 as by suitable bolts or otherwise. The free threaded ends of the adjusting bolts 13 and 14 project through suitable openings provided in the flanged portion of the gland 10, their outer ends being engaged by the nuts 15 by means of which the gland 10 is readily manipulated to adjust or compress the packing 9.

The head member 2 is provided with a suction or admission opening 16, the axis of which is adapted to substantially align with the axis of the impeller shaft 7 when the casing 1 and head member 2 are bolted together. The admission opening 16 is surrounded by a suitable flange 17 for connecting to a pipe line. The inner face of the head member 2 is provided with an annular channel which is adapted to coöperate, when the head member 2 is bolted to the casing 1, with a similar channel provided in the inner face of the casing 1, thereby forming an annular discharge passage 18 about the periphery of the pump. The discharge chamber 18 is not made with the usual variable cross section area as in pumps of the volute type, but is of a uniform cross section area throughout.

A delivery or discharge opening 19 is provided at the topmost point of the pump, as there is less danger of air accumulation in the top of the pump, which must be considered foremost as air pockets would lose the priming of the pump and stop operation of the same. As shown in Fig. 4, the discharge opening 19 has an equal angle of approach from either side of the pump, each of the side walls 20 and 21, of the discharge neck being substantially tangent to the outer periphery of the discharge chamber 18. The width of the passage 22 which affords communications between the discharge chamber 18 and the discharge neck is reduced to considerable less than the diameter of the discharge chamber, thereby forming a restricted throat portion

to effectively prevent the formation of eddy current pockets within the discharge neck. The casing 1 and head member 2 are provided with suitable flanges which, when the casing and head member are bolted together, form a continuous flange 23 about the upper end of the discharge opening 19 to facilitate connection with a discharge pipe line.

An open type impeller 24 is mounted upon the inner end of the impeller shaft 7 and may be driven by any rotative motive power such as the motor 25 shown in Fig. 1. The freedom from end thrust which I am able to secure by this construction is of particular importance in permitting the impeller shaft 75 to be coupled directly to the motor shaft. No thrust or axial bearing is required in addition to the regular motor bearings. The blades or vanes of the impeller 24 may be integral with a center boss or may be otherwise rigidly secured upon the impeller shaft 7, it being understood that the impeller as well as the interior parts of the pump are preferably made of non-corrodible material such as lead when sulfuric acid is to be conveyed. The blades of the impeller 24 are recessed adjacent the admission opening 16, as shown at 26, it being apparent that the total depth of the impeller blades from the flat inner face 27 of the casing 1 to the admission opening 16 is greater than is ordinarily found in pumps of this type, this is to allow the recess 26 to be formed of a sufficient depth. It is preferable that the diameter of the recess 26 be substantially equal to the diameter of the admission opening or suction opening 16, the axis of the admission opening alining with the axis of the recess when the casing and head member are clamped together. This form of impeller 105 has been found to admirably provide for the admission of fluid into the pressure chamber with a minimum velocity of whirl.

The blades or vanes of the impeller 24 taper in depth as shown in Figs. 2 and 3, 110 their greatest depth being at the recess 26, as has been explained, from where their front edges taper toward the periphery of the impeller where they reach their least depth. The flat inner face 27 of the casing 1 forms the inner wall of the pressure chamber in which the impeller 24 is adapted to rotate, the outer wall thereof being formed by the coöperation of the head member 2 therewith. It will be seen that the cross sectional area of the pressure chamber is greater at the admission opening than at the periphery or point of discharge, thereby effectively preventing the formation of eddy current pockets between the pressure chamber and the discharge chamber 18.

In Figs. 5 and 6 I have diagrammatically illustrated the method I employ for controlling the direction and amount of end thrust. If the recess 26 were formed of too great a 130

depth, for the speed of rotation and quantity of liquid to be pumped, as shown in Fig. 5, the incoming liquid, the flow of which is indicated by the dotted lines and arrows, 5 upon entering the impeller recess, would change its direction of flow, that is, would receive a centrifugal motion too far in front of the face 28 of the impeller 24, and atmospheric pressure on the shaft would produce 10 a suction pocket, as shown at 29, the tendency of which would be to pull the impeller 24 toward the incoming liquid as indicated by the arrow.

In Fig. 6 I have illustrated the result of 15 making the recess 26 too shallow. In this case sufficient space has not been allowed for the incoming liquid to change its direction of flow, upon entering the impeller recess 26, consequently a portion of the liquid, 20 the amount of which obviously depends upon the depth of the recess, strikes the face 28, thereby producing a thrust along the impeller shaft 7, away from the incoming liquid, as indicated by the arrow. I therefore 25 make the depth of the recess such that the impact of the liquid at the inlet and the atmospheric pressure on the shaft balance each other, eliminating all end thrust.

In determining the depth of recess for 30 any particular use or installation, I proportion it to the speed of the impeller, the pressure of the liquid at the point of inlet, and the density or specific gravity of the liquid to be pumped, but in any event I 35 make the recess deeper than the width of the peripheral discharge. I do this because the longitudinal depth of the liquid is greater at the point where it crosses the longitudinal edges of the cut-out portions of the blades 40 than it is at the relatively long peripheral outlet. By this I mean that the unobstructed peripheral area of the recess formed by cutting the blades as shown is greater than that area required by the liquid 45 at the point of passage through said unobstructed peripheral area of the recess, and at the velocity imparted to it by the impeller. By unobstructed peripheral area is meant the area between adjacent cuts in adjacent blades. It is obvious that in an impeller constructed as described, only the edges of the blades of the impeller receive 50 the impact of the liquid, therefore presenting a minimum of surface to receive such impact of the flowing liquid, and that any pressure on the impeller parts resulting from such impact must be for the most part radial and not longitudinal, and that in consequence of this I am enabled to produce a 55 pump of this character in which the end thrust on the impeller shaft is controlled or entirely eliminated.

Centrifugal pumps only possess the tendency to produce thrust toward the incoming 60 liquid when lifting from a point below the

level of the pump, which is not a condition of normal operation for low head centrifugal pumps, such as the present invention. In such pumps the liquid is almost always delivered to the pump, and the thrust is due 70 to the velocity of impact of the liquid against the exposed area of the impeller. This area is that which lies at an acute angle to the direction of flow of the liquid and I eliminate such an area by the cutting of the impeller blades to form the recess described. 75

Although I have described my invention in connection with systems wherein acids or other corrosive liquids or fluids are conveyed, it is equally as well adapted for any 80 pumping system. It is now apparent that I have provided a pump which is simple, reliable and durable and wherein access to the interior parts is easily had for cleaning, repairing and interchanging impellers, to 85 secure a different recess depth when either the speed of rotation or capacity of the pump is changed.

I claim:

1. In a pump adapted to receive fluid 90 under a head, a pressure chamber, a casing forming the inner wall of said pressure chamber, a head member forming the outer wall thereof, a shaft carrying an open impeller adapted for rotation in said pressure 95 chamber, the blades or vanes of said impeller being recessed at the axis thereof, said head member being provided with an admission opening adjacent the recessed portion of said impeller blades, a discharge 100 chamber surrounding said crusher chamber, a radial discharge throat the side walls of which approach a discharge opening substantially tangent to the outer periphery of said discharge chamber and a discharge passage connecting said discharge chamber and said discharge throat, the depth of said passage being less than the diameter of said discharge chamber. 105

2. In a pump adapted to receive liquid 110 under a head, a stationary pressure chamber, the cross sectional area of said pressure chamber being substantially greater at the admission opening than at the point of discharge, a discharge chamber surrounding 115 said pressure chamber, the cross sectional area of said discharge chamber being substantially equal throughout and a contracted peripheral discharge passage connecting the discharge chamber with the 120 pressure chamber in communication with said discharge chamber.

3. In a pump having an open impeller adapted to receive liquid under a head, a casing having an annular channel therein, 125 a head member adapted to be clamped to said casing, said head member having an annular channel adapted to coöperate with the channel in said casing to form a discharge chamber, the coöperation of said 130

head member with said casing forming a discharge opening; a discharge throat the side walls of which approach said discharge opening substantially tangent to the outer 5 periphery of said discharge chamber, the depth of the discharge throat at the discharge chamber being substantially less than the diameter of said discharge chamber, to form a restricted communication 10 therebetween.

4. In a pump adapted to receive fluid from a head, a stationary casing, a head member adapted to be clamped thereto, said casing having an inlet at the center of said 15 head and having a peripheral discharge chamber of substantially uniform cross section, and a radially extending discharge throat communicating with said chamber through a restricted passage.

20 5. In combination, a substantially closed casing having an axial inlet and a peripheral outlet, a rotatable shaft projecting into said casing in axial alinement with said inlet, an open impeller on said shaft within 25 said casing, said impeller comprising blades extending substantially radially from said shaft to said outlet, said blades being cut away at their inner ends to form a recess substantially equal in diameter to the inlet 30 and of such a depth as to eliminate axial thrust in said impeller shaft, said pump being adapted to receive fluid from a head.

6. In a pump adapted to receive fluid from a head, a casing, a head member 35 adapted to be clamped thereto, a rotary impeller comprising a shaft having a plurality of blades or vanes secured thereto, the blades or vanes of said impeller being recessed at the axis of the impeller, the depth 40 of said recess being proportioned to the capacity of the pump and the speed of the propeller to control the axial thrust in said impeller shaft.

7. A rotary impeller for centrifugal 45 pumps comprising a shaft carrying a plurality of blades or vanes, the blades or vanes of said impeller being recessed at the axis of the impeller, the depth of said recess being proportioned to the capacity of the 50 pump and the speed of the impeller to control the axial thrust in said impeller shaft.

8. The combination in a pump adapted to receive fluid under a head, of a stationary 55 casing, a head member adapted to be clamped thereto, said casing having an inlet at the center of said head member and a peripheral discharge chamber, a radially

extending discharge throat communicating with said chamber through a restricted passage and a rotatable open impeller in said 60 casing in axial alinement with said inlet, said impeller comprising blades extending radially from said inlet to the outlet, said blades being recessed at the axis of the impeller, the depth of said recess being 65 proportioned to the capacity of the pump and the speed of the impeller to control the axial thrust in said impeller shaft.

9. In a pump for operation in a continuous fluid column and for corrosive fluids, 70 a body having the interior parts thereof formed of non-corrodible material, said body having a bore therein for an impeller shaft, a shaft in said bore projecting into the pump, an admission opening axially in 75 line therewith, a discharge opening and an open impeller of non-corrodible material comprising a plurality of independent blades mounted on the inner end of said shaft and extending radially therefrom, 80 said blades being provided with a recess adjacent said inlet, the depth of said recess being proportioned to the capacity of the pump and the speed of the impeller to control the axial thrust in said impeller shaft. 85

10. A rotary impeller for low head centrifugal pumps comprising a shaft carrying a plurality of blades or vanes, the blades or vanes of said impeller being recessed at the axis thereof, the depth of said recess being 90 proportioned to the capacity of the pump and the speed of the impeller to control the axial thrust in said impeller shaft, the greatest depth of said blades or vanes being 95 at said recess from where they taper, reaching their least depth at the periphery of the impeller.

11. In a pump of the class described, a substantially closed casing having a central inlet and a peripheral outlet, a rotatable 100 open impeller in said casing in axial alinement with said inlet, said rotatable impeller having blades extending radially from said inlet, said blades being cut away at the center of the impeller to form an axial recess, 105 the depth of said recess being proportioned to the capacity of the pump and the speed of the impeller to control the axial thrust in the impeller shaft and said pump adapted to receive fluid from a head. 110

In witness whereof I hereunto subscribe my name this 7th day of March, A. D. 1918.

HARRY E. LA BOUR.

It is hereby certified that in Letters Patent No. 1,355,982, granted October 19, 1920, upon the application of Harry E. La Bour, of Chicago Heights, Illinois, for an improvement in "Centrifugal Pumps," errors appear in the printed specification requiring correction as follows: Page 2, lines 46-47, for the word "section" read *sectional*; page 3, line 101, claim 1, for the word "crusher" read *pressure*; and that the said Letters Patent should be read with these corrections therein that the same may conform to the record of the case in the Patent Office.

Signed and sealed this 30th day of November, A. D., 1920.

[SEAL.]

L. B. MANN,
Acting Commissioner of Patents.

Cl. 253—200.
